UNITED STATES PATENT OFFICE.

WELLINGTON PARKER KIDDER, OF BOSTON, MASSACHUSETTS, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,146,578.

Specification of Letters Patent. Patented July 13, 1915.

Application filed April 22, 1909. Serial No. 491,580.

To all whom it may concern:

Be it known that I, WELLINGTON P. KIDDER, a citizen of the United States, residing at Boston, in the county of Suffolk and State 5 of Massachusetts, have invented certain new and useful Improvements in Type-Writing Machines, of which the following is a full, clear, and exact description, such as will enable others skilled in the art to which it 10 appertains to make and use the same.

This invention relates to typewriting machines and more particularly to that type of machine wherein printing is effected by pressure rather than by impact or 15 cushion.

One of the objects of the present invention is to provide a new and improved form of platen.

Another object is to provide a new and 20 improved form of support for the paper upon which printing has been effected whereby erasures may be made with greater facility than in machines of this type as hitherto constructed.

25 Other objects will be in part obvious and in part pointed out hereinafter.

The invention accordingly consists in the features of construction, combinations of elements and arrangement of parts which 30 will be exemplified in the construction hereinafter set forth, and the scope of the application of which will be indicated in the following claims.

In the accompanying drawings, wherein 35 is illustrated one of the various possible embodiments of my invention, Figure 1 is a longitudinal sectional view of the machine, showing the devices which constitute the present invention; Fig. 2 is a plan view of 40 Fig. 1.

Similar reference characters refer to similar parts in both views of the drawings.

Referring now to the drawings, 1 represents the framework of the machine supporting the top plate or bed 2 upon which rests the type bars 3 and across which they are projected when they are actuated to effect printing. A top plate 4 acts as a guide for the upper edges of the type bars and the forward ends of said bars are guided to the proper position upon the platen by means of a vertically-disposed guide 5 secured to the front end of the bed 2. The front wall of the machine is provided with a ledge 6, 45 upon which are supported blocks 7. These blocks support the type bar actions which are connected by means of links 8 to the type bars 3 and by means of suitable connecting bars or links 9 to the key levers 10.

To the frame of the machine 1 is attached 60 a bracket 11 as by means of screws 12, and from either end of this bracket extends an upright 13 and 14. These uprights are connected, as by means of a bar 15, preferably of truss form, as shown, so as to furnish 65 a rigid construction which will not yield under the pressure exerted by the type bars when they are projected against the platen.

The bar or truss 15 intermediate its ends is provided with a beveled face 16 against 70 which rests a block 17 having an oppositely beveled face 18. This block is provided with suitable ears or dovetails which receive the carriage block 19, block 19 being in turn provided with ways for receiving a required 75 extension of the carriage hereinafter described. The block 17 is tapped out and engages a threaded rod 20 which may be rotated by means of a knob 21 whereby the wedge block 17 will be shifted sidewise a 80 greater or less distance, thus moving the face 22 of the block 17 forwardly or rearwardly with respect to the beveled face 16 of the truss.

The carriage 23 rides upon a rail 24, and 85 the platen frame 25 slides vertically upon the carriage and is shiftable for different case printing by means of a block 26 and link 27 connected with the shifting mechanism, not shown herein, block 26 riding in 90 a channel bar 27' which extends longitudinally of the platen frame. The platen frame 25 is composed of a pair of side pieces 28 and 29 respectively, connected at their upper portions by means of a horizontally disposed plate 30. This plate is turned downwardly at its forward portion to provide a printing platen 31, the rear portion thereof constituting the angularly disposed coupling extension 32 which rides in the block 19 100 hereinbefore described. Beneath plate 30 and adjacent the platen is provided a feed roll 33. Plate 30 is also provided with a longitudinally extending aperture 34 through which extends a paper table 35, said 105 paper table being pivoted to the platen frame as by means of pivot screws 36. The paper table at its forward end supports pa-

per feed rolls 37 which coöperate with the feed roll 33 to feed the paper which is passed downwardly through aperture 34, forward between the rolls and then upward 5 over the platen. A leaf spring 38 presses the lower end of the paper table upwardly and holds the feed rolls 37 carried thereby in engagement with the feed roll 33 carried by the platen carriage. A knob 39 is carried upon the feed roll shaft by means of which said roll 33 may be turned to feed the paper. A curved guide plate 41 depends from the under side of the plate 30 and co-operates with the paper table in guiding the 10 paper between feed rolls 33 and 37.

42 indicates an erasing table which is supported upon the upper surface of plate 30, the forward end of this plate being preferably curved as shown.

20 43 indicates a graduated scale on the upper part of the center tie 15 substantially parallel with the face 16. This scale may be divided into any number of suitable parts, each denoting a distance between the type 25 bar at the end of its stroke and the platen equal to the thickness of one sheet of typewriter paper. Coöoperating with the scale 43 is a pointer 44 on the wedge block 17, whereby the operator will know by the number indicated on the scale the space existing 30 between the extended type bar and the platen. There is also mounted on the wedge block 17 a gaging device for adjusting the platen when paper of an unusual thickness 35 is used when the scale indicator would not be sufficiently accurate. This device comprises an extended arm 45 adapted to engage with a fixed block 46 on the upper part of the center tie 15, when the pointer 44 indicates zero on the scale 43. As the wedge 40 block 17 is moved to the left on rotation of the shaft 20 by the knob 21, the arm 45 moves away from the block 46 a distance corresponding to the number indicated on 45 the scale 43, thus when it is desired to gage a certain thickness of paper or the thickness of several sheets, the paper is inserted between the gaging surfaces of the members 45 and 46, which have previously been separated. The gaging face 45 is then closed 50 upon the paper, pressing it against the gaging face of the block 46 by moving the wedge member 17 to the right. When the gaging faces have closed upon the paper 55 with the proper pressure, the paper is then slid from between said faces and inserted in the carriage, which will be positioned properly for printing with the desired degree of pressure.

60 Having thus described the construction of this embodiment of my invention, the operation thereof may now be understood. When it is desired to change the position of the platen with respect to the normal printing 65 plane, such operation may be conveniently

effected by merely turning knob 21 which moves the wedge block 17 along the beveled surface 16 of the truss, thereby moving the entire carriage with the platen forwardly or rearwardly. The paper may be 70 conveniently inserted through aperture 34 whereupon it will be grasped by the feed rolls and fed forwardly and upwardly over the platen. It will, accordingly, be seen that I have provided mechanism well adapted 75 to attain the several ends and objects of my invention in a simple yet efficient manner.

One of the advantages inherent in the present construction is that an absolutely 80 rigid backing is afforded for the platen carriage, the construction being such that the position of the platen with respect to the normal printing plane may be conveniently varied. When the paper is inserted through 85 the aperture of the carriage it will be guided and fed over the platen, the table 42 affording a convenient support for the paper when it is desired to make erasures.

As many changes could be made in the 90 above construction and many apparently widely different embodiments of this invention could be made without departing from the scope thereof, it is intended that all matter contained in the above description 95 or shown in the accompanying drawings shall be interpreted as illustrative and not in a limiting sense.

Having described my invention, what I claim as new and desire to secure by Letters Patent is:

1. In a typewriting machine, the combination with the carriage, of a plate located thereon and having its forward portion turned downwardly to form a platen surface, paper feed rolls located beneath said plate and adjacent said downwardly-turned portion, said paper rolls being adapted to feed the paper forwardly and upwardly over said downwardly turned portion, and an aperture formed in said plate through which the paper may be passed to said feed rolls.

2. In a typewriting machine, the combination with the carriage, of a plate fixed thereon, a platen formed by a downwardly turned portion of said plate, a feed roll carried by the platen frame beneath said plate and adjacent said platen, an aperture formed in said plate behind the platen, a paper table extending through said aperture, and feed rolls carried by said paper table and co-operating with said first-mentioned feed roll to feed the paper forwardly and upwardly over the platen.

3. In a typewriting machine, in combination, a platen carriage comprising side pieces, a plate connecting said side pieces, a platen formed by a downwardly turned portion of said plate, paper feed rolls sup-

ported beneath said plate adjacent said platen, said plate being provided with a paper-receiving aperture behind the platen, a pivotally mounted paper table extending 5 downwardly through said aperture, a feed roll carried by said paper table which co-operate with said first-mentioned feed rolls to feed paper inserted through said aperture forwardly and then upwardly over the 10 platen, and spring means engaging said paper table for holding the feed roll against the paper.

4. In a typewriting machine, in combination, a carriage comprising supporting members and a plate connecting the same, said plate having a downwardly turned portion which provides a printing platen, a feed roll supported beneath said plate adjacent said platen, said plate having a paper-receiving 15 aperture behind the platen, a paper table extending downwardly through said aperture, means pivotally supporting said paper table upon the platen carriage, feed rolls carried by the paper table which co-operate 20 with said first-mentioned feed roll to feed paper inserted through said aperture forwardly and then upwardly over the platen, and spring means engaging said paper table for holding the feed rolls carried thereby 25 in engagement with said first-mentioned feed roll.

5. In a typewriting machine, in combination, a vertically movable platen frame comprising a top plate, the forward portion of said top plate being turned downwardly to provide a platen, a feed roll supported upon the platen frame beneath said plate and adjacent the rear portion of the platen, said 30 plate being provided with a paper-receiving aperture located behind the platen, a paper

table extending downwardly through said aperture, means for pivotally supporting said paper table, and feed rolls journaled upon the paper table and engaging said first-mentioned feed roll whereby paper inserted 45 through said aperture may be fed forwardly and then upwardly over the platen.

6. In a typewriting machine, in combination, a platen frame comprising a horizontally disposed top plate, a platen formed by a downwardly turned portion of said plate, said plate being provided with a paper-receiving opening, a paper table extending downwardly through said opening, a feed roll carried by the platen frame beneath said 50 plate and adjacent the platen, feed rolls carried by the paper table, and spring means engaging the paper table adapted to hold the feed rolls in engagement.

7. In a typewriting machine, in combination, a platen frame comprising a plate having a downwardly turned portion which provides a printing platen, and an erasing table located upon said plate adjacent the 55 platen.

8. In a typewriting machine, in combination, a platen frame comprising a pair of end members, and a plate rigidly connecting said end members, said plate having a downwardly turned portion which provides a 60 printing platen and an angularly disposed coupling portion, and a rigid abutment to which pressure on the platen is transmitted through said coupling.

In testimony whereof I affix my signature, 75
in the presence of two witnesses.
